PROCESS OF MAKING MIXED GAS

Filed March 21, 1921

UNITED STATES PATENT OFFICE.

HARALD NIELSEN, OF MUSWELL HILL, AND JAMES RANKIN GARROW, OF WIMBLEDON, ENGLAND.

PROCESS OF MAKING MIXED GAS.

Application filed March 21, 1921, Serial No. 454,186, and in Great Britain February 23, 1920.

(GRANTED UNDER THE PROVISIONS OF THE ACT OF MARCH 3, 1921, 41 STAT. L. 1313.)

- This invention relates to methods of distilling carbonaceous materials of the kind in which the so-called sensible heat of producer gas and water gas (as distinguished from the heat of combustion) is utilized to effect low temperature distillation or carbonization by passing the gas from producers through retorts containing the material which is to be treated.
- 10 In methods of this kind the usual proposal has been to pass all the gases evolved by a single producer through the low temperature retort or retorts. In such cases the quantity of producer gas which it has been proposed to use being far in excess of the quantity actually required to effect low temperature distillation would result in the hydrocarbon vapors or retort gas evolved during treatment in the retort becoming mixed with an extremely large quantity of producer gas. Consequently, the recovery of the tar oils by condensation and of the permanent light hydrocarbon oils by oil washing would be extremely difficult, while 25 the oil washing plant required for the purpose would necessarily be of large dimensions and costly if constructed to treat the great volume of mixed gases thus produced, and it is the chief object of the present invention to overcome the difficulty of treating in tar oil condensers and in oil washers a mixture containing a large excess of producer gas.
- According to the present invention a multiplicity of gas producers are employed, one of said producers being situated adjacent to the retort and being of such capacity or being supplied with a measured quantity of fuel which is such that the quantity of producer 35 gas which is evolved, while containing or possessing sufficient so-called sensible heat to effect the requisite heating of the carbonaceous material in the retort, will not unduly dilute the retort gas, the intermingled producer gas and retort gas after leaving the retort and after being treated so as to condense or remove the volatile oils contained therein, being mixed in a suitable receptacle, such as an ammonia scrubber, with producer gases which are withdrawn from and passed directly into such receptacle from the auxiliary or supplementary gas producers. The semi-coke obtained from the retort which latter is preferably of the revolving
- type and preferably adapted to provide sufficient coke for use in all the producers of the series is collected after treatment in a suitable receptacle and a measured quantity of this material is employed to feed the producer which is in communication with the retort, the quantity supplied being such as to generate in the producer only the requisite quantity of producer gas which is required for heating the material in the retort and the excess of retort coke being available to feed the supplementary producers of the series. Additionally, by reason of the degasification of the coal at a low temperature, there is formed low temperature carbonization coke which is divided into two portions, each of which is completely gasified. The producer gases from the auxiliary producers (which gases contain ammonia but little or no tar oil vapors) are led as aforesaid direct to the ammonia scrubbers where they meet the combined producer and retort gas obtained from the distillation of the carbonaceous material within the retort after said gases have passed through the condensers and oil washers. Owing to this arrangement, and as the gas produced from the auxiliary producers does not pass either through the retort or through the tar oil condensers and oil washers the mixed producer and distillation gases are not diluted until mixed with the auxiliary producer gas in the ammonia washers thus rendering the extraction in the condensers and washers of the oil vapors easier and less expensive than heretofore.
- In order that the said invention may be clearly understood and readily carried into effect the same will now be described more fully with reference to the accompanying drawing which shows a side elevation of the apparatus with parts in section of the invention for the purpose of clearness of illustration.
- Referring to the drawing *a* is a hopper or container for the black coal, bituminous or otherwise, lignite, brown coal, peat or wood for feeding the retort or rotary drum *c*, while *b* is a feeding pipe by means of which the raw fuel in the hopper *a* is fed into the low temperature carbonization retort *c*, the pipe *b* also serving to conduct the mixed producer and distillation gases away from the retort. *d* is a fixed annular casing surrounding one end of the distilling or carbonization retort *c*.

izing retort *c* wherein the carbonized fuel treated in the retort *c* is collected after falling through the opening *c'* in the retort *c*, *e* is the carbonized fuel off-take from the retort *c*, it being observed that the semi-coke drops from the fuel off-take *e* into the hopper *t*, and *f* is a conveying plant of any well known type for conveying by means of chutes *g* the heated and partially coked material 10 into the overhead bunkers *q*—from which it is fed into the gas producers *p'*, *p²*, *p³*, and *h*. *h* is the producer set apart for generating producer gas for use in heating the carbonaceous material in the retort *c*, while *p'*, *p²* 15 and *p³* are the auxiliary gas producers. The producer gas may be made from air alone or else from air and steam so as to produce in the latter case so-called semi-water gas. *v* is the pipe for admitting air to the producer *h*, and *v'* is the pipe for admitting steam. *i* is a pipe for conducting the gas from the gas producer *h* into the retort *c*, both of said pipes *b* and *i* passing through stuffing boxes *x* at each end of the retort *c*. *j* is a cooler or 20 condenser for the mixed gases which leave the retort *c*, and *k* is an absorption apparatus for the recovery from said mixed gases of condensable and absorbable hydrocarbon products contained therein. A pipe *l* conducts the stripped gases from the absorption apparatus *k* to an ammonia absorber *m* which latter also deals with the ammonia obtained in the auxiliary gas producers *p'*, *p²*, *p³*. Branch pipes *o* carry the producer gas 25 directly from the auxiliary gas producers *p'*, *p²*, *p³*, to a gas main *n* which is also connected to the absorber *m* so that all the gases produced from all four producers as also from the retort *c* are eventually mixed or united 30 therein and from which the gases are conducted by means of outlet pipe *r* to further cleaning apparatus if so desired.

In order to prevent the raw material from adhering to the walls of the retort *c* whilst 45 undergoing heat treatment a certain amount of dry material may be introduced along with the raw material or crude fuel, or scrapers or similar devices of any well known type may be employed to keep the walls 50 clear or to facilitate the movement of the raw material undergoing treatment through the retort.

If desired, the heated and partially coked material, which is delivered from the fuel 55 off-take *e* to the hopper *t*, instead of being conducted to the bunkers, may be removed from the hopper in its semi-coked condition.

The arrows shown on the drawing indicate the direction of flow of the gases as also 60 that of the material under treatment.

It will thus be seen that an apparatus constructed according to the present invention provides a continuous method for the production of solid and gaseous fuel with 65 by-product recovery without undue dilution

of the distillation gases from the carbonizing retort. It will thus be seen that by the present method three distinct combustible gases are produced having different characteristics and heating values, said method 70 consisting in conducting raw carbonaceous material through a rotating low temperature retort of sufficient capacity to provide the coke necessary for use in a multiplicity of gas producers and through which a thin 75 layer of carbonaceous material is fed continuously, delivering the semi-coke produced in the retort into a series of gas producers where it is fully gasified, and, in cases where air only is admitted to the gas producers, produces a heating gas of a specific 80 heating value, namely, 150 B. t. u. per cubic foot; passing the gas generated in one of said producers into said retort, withdrawing the mixed producer and distillation gases 85 from the retort; condensing, washing or otherwise removing the volatile oils therefrom and thereby producing a mixed gas of a higher heating value, namely, 250 B. t. u. per cubic foot; passing the said mixed 90 gas into a receptacle, and conducting directly into said receptacle the producer gas from the other said gas producers so as to mix the same with the treated gases from the retort, thereby producing a third gas also 95 of a different heating value, namely, 175 to 180 B. t. u. per cubic foot. In cases where air and steam are admitted to the producers so as to produce so-called water gas the heating value of the gas obtained from the producers is 300 B. t. u. per cubic foot; that of the mixed gas obtained after the oils are extracted 400 B. t. u. and, after admixture with the semi-water gas, 350 B. t. u. per 100 cubic foot.

What we claim and desire to secure by Letters Patent of the United States is:—

1. A process of making mixed gas with by-product recovery from solid carbonaceous materials, which consists in conducting the raw fuel into a rotating low temperature retort of sufficient capacity to provide the coke necessary for use in a plurality of gas producers, and through which retort a relatively thin layer of carbonaceous fuel is fed continuously, carbonizing the fuel with hot producer gas, delivering the coke carbonized in the retort into a series of gas producers, one of said producers being in communication with the retort, generating producer gas by blasting the coke in said producer with an aeriform or gaseous fluid, passing the hot gas from said producer into said retort and thereby distilling the fuel, withdrawing the mixed producer and distillation gases from the retort, condensing, washing or otherwise removing the volatile oils from the mixed gases, passing the said gases into a receptacle, and conducting directly into said receptacle the 110

120

125

130

producer gas from another of said gas producers so as to mix the same with the treated distillation gases from the retort.

2. A method of making mixed coal gas and producer gas, which comprises degasification of coal at a low temperature by hot producer gas, thereby forming low temperature carbonization coke, dividing said coke into two portions, completely gasifying one portion by blasting with an aeriform or gaseous fluid, passing the generated producer gas into direct contact with the coal to heat the latter to produce the low temperature carbonization coke and coal gas, completely gasifying the second portion of the coke by blasting with an aeriform or gaseous fluid to form producer gas, and mixing the gas produced from the first portion of the coke with that from the second portion.
3. A method of making mixed coal gas and producer gas, which comprises degasi-

fication of the coal at a low temperature by hot producer gas, thereby forming low temperature carbonization coke, dividing said coke into two portions, completely gasifying 25 one portion by blasting with an aeriform or gaseous fluid, passing the generated producer gas into direct contact with the coal to heat the latter to produce the low temperature carbonization coke and coal gas, completely 30 gasifying the second portion of the coke by blasting with an aeriform or gaseous fluid to form producer gas, mixing the gas from the first portion of the coke with that from the second portion, and so dividing the low 35 temperature coke that the gas produced by the complete gasification of the first portion will produce sufficient heat to cause low temperature degasification of a mass of coal equal to the original mass.

HARALD NIELSEN.
